(Cl. D15—1)

FIG. 1.

FIG. 2.

FIG. 4.

FIG. 3.

FIG. 5.

FIGURE 1 is a pictorial view of a chair or similar article of furniture incorporating my new design;

FIG. 2 is a side elevation of the chair or similar article of furniture;

FIG. 3 is a sectional view, taken along a plane indicated by line 3—3 of FIG. 2; and

FIGS. 4 and 5 are enlarged sectional views, taken along planes indicated by lines 4—4 and 5—5 of FIG. 3.

The dominant feature of the design resides in the portion shown in full lines on the drawing and consists primarily in the base portion which is shaped as shown.

I claim:

The ornamental design for a chair or similar article of furniture, substantially as shown and described.
